UNITED STATES PATENT OFFICE.

WARD S. IRELAND, OF OWENSBORO, KENTUCKY.

TYPE-WRITING MACHINE.

1,098,114.

Specification of Letters Patent. Patented May 26, 1914.

Application filed March 11, 1913. Serial No. 753,631.

To all whom it may concern:

Be it known that I, WARD S. IRELAND, a resident of Owensboro, in the county of Daviess and State of Kentucky, have invented certain new and useful Improvements in Type-Writing Machines; and I do hereby declare the following to be a full, clear, and exact description of the invention, such as will enable others skilled in the art to which it appertains to make and use the same.

This invention relates to improvements in typewriting machines and more particularly to ribbon mechanism therefor,—one object of the invention being to so construct ribbon mechanism that the automatic shifting of the ribbon shall be accurate and sure and so that the normal feeding of the ribbon shall be uniform.

20 A further object is to provide ribbon operating and shifting mechanism which shall be simple in construction, comprising a comparatively small number of parts and which shall not be liable to get out of order.

25 With these objects in view, the invention consists in certain novel features of construction and combinations of parts as hereininafter set forth and pointed out in the claims.

30 In the accompanying drawings, Figure 1 is a longitudinal sectional view of a type-writing machine embodying my improvements. Fig. 2 is a front elevation, partly in section, showing the ribbon mechanism, and Fig. 3 is a view partly in plan and partly in section showing the ribbon mechanism.

1 represents the frame of the machine in the upper portion of which a platen 2 is located and mechanism is provided for 40 moving a strip 3 of paper step-by-step in front of this platen. This paper feeding mechanism forms no part of the invention herein described and claimed and a detail explanation of the same is unnecessary. It 45 might be stated however that the paper feeding mechanism is connected with and operated by the movements of a universal bar 4, the latter being actuated by arms 5 on key levers 6.

50 The type bars 7 of the machine are pivotally mounted in a notched bar 8 and connected at their lower ends with the key lever arms 5.

Two vertical shafts 9 are mounted in the 55 framework and upon the upper ends of these shafts, ribbon reels 10 are located and

the ribbon 11 is guided from one reel to the other and between the type of the type-bars and the platen by means of suitable guide rolls 12. A beveled pinion 13 is secured to the lower end of each vertical shaft 9 and mesh with pinions 14 on two shafts 15 mounted in the framework. The shafts 15 are disposed in axial alignment with each other but are independently operable and to each of said shafts a ratchet wheel 16 is secured. Guides 17 are provided in the framework for the accommodation of pawls 18,—said pawls being pivotally connected with the universal bar 4 and, passing between said guides, engage the ratchet wheels 16. Dogs 19 are pivoted to the guides 17 and also engage the ratchet wheels 16 to prevent retrograde rotation of the shafts to which said ratchet wheels are secured and consequently to prevent retrograde movement of the ribbon feed.

L-shaped levers 20 are pivotally connected at their upper ends to a bar or rail 21 of the framework and the approximately horizontal arms of these L-shaped levers project under the respective pairs of dogs or pawls 18—19,—said arms 22 being vertically movable in slotted guides 22^a secured to the guides 17. A longitudinally movable shift 85 bar 23 is mounted in the framework above the ratchet devices hereinbefore described and provided with an arm 24 which projects through a slot 25 in the top of the framework and terminates in position to be 90 grasped by the operator. The ends of the shift bar 23 are pivotally connected with the L-shaped levers 20, so that when said shift bar is moved longitudinally in one direction, one of the L-shaped levers 20 will 95 be operated to cause its horizontal member 22 to raise one pair of dogs or pawls 18—19 out of engagement with the ratchet wheel with which they co-operate, and to permit the horizontal member of the other L-shaped 100 lever to descend and allow the other pair of dogs or pawls 18—19 to engage the other ratchet wheel. The machine frame is made with a hollow-member 26 which receives a spring-pressed plunger 27 to bear against 105 the shift bar and hold it in the position to which it may be moved, the tension of the spring 28 for this plunger being adjustable by means of a screw 29.

I have above described the devices by 110 means of which the direction of feed of the inking ribbon can be shifted manually and

I will now proceed to explain the devices whereby the shifting of the inking ribbon is automatically effected.

Each ribbon reel is provided with a hub 30 which depends below the reel as clearly shown in Figs. 1 and 2. Each of these hubs is made with a recess 31 which is normally spanned by spring actuated hinged section 32, the spring tending to open this hinged section when the ribbon shall have become exhausted from the reel as shown at the right hand side of Fig. 3, but when ribbon is on the reel, the hinged section 32 will be closed and held so by the ribbon as shown at the left in Fig. 3. L-shaped arms 33 are pivotally attached to the framework and in the free ends of the short members of these arms, wheels 34 are mounted and adapted to run on those portions of the sleeves or hubs 30 which depend below the ribbon reels, such engagement of the wheels 34 with the sleeves or hubs 30 being insured by means of spring pressed plungers 35. Arms 36 project upwardly from the shift bar 23 and their upper ends are disposed between the long members of the L-shaped arms 33 and the hubs 30. When the inking ribbon shall have become exhausted from one of the ribbon reels, the hinged section 31 of the hub 30 will be opened by the action of its spring and the spring-pressed plunger 27 will operate to cause the roller 34 carried by the L-shaped arm 33 to move in a direction to enter the recess in said hub. The roller 34 on arm 33 will first engage the hub 30 at one edge of the recess 31, and the pressure exerted against said arm by the spring-pressed plunger 35, will cause the reel-hub to be positively moved sufficiently to insure the entrance of the wheel 34 into recess 31. Such movement will permit the arm 33 to engage one of the arms 36 of the shift bar 23 and move the latter longitudinally to operate the L-shaped lever 20 in the manner above explained to disengage one pair of dogs or pawls from one ratchet wheel and permit the other pair of dogs or pawls to engage the other ratchet wheel.

It is apparent that when the key levers 50 are operated, the universal bar 4 will be actuated to operate the dogs or pawls 18 and thus cause motion to be transmitted to one or the other of ratchet wheels 16 and to one of the ribbon reels and that when the shifting devices are operated either manually or automatically, motion will be transmitted to the other ribbon reel for moving the inking ribbon in the reverse direction.

Having fully described my invention what 60 I claim as new and desire to secure by Letters-Patent, is:

1. In ribbon mechanism for typewriting

machines, the combination with two shafts, alining shaft sections disposed at right angles to said shafts, and gearing between 65 said shaft sections and said shafts, of a ratchet wheel carried by each shaft section, a movable universal bar, dogs or pawls carried by said universal bar and adapted to engage the respective ratchet wheels, other 70 dogs pivoted to a fixed support and adapted to engage the ratchet wheels, pivoted arms projecting under the respective pairs of dogs, and a longitudinally movable shift bar pivotally connected with the respective 75 arms.

2. In ribbon mechanism for typewriting machines, the combination with two shafts, ribbon reels thereon, shaft sections disposed at right angles to said shafts, and gearing 80 between the shaft sections and shafts, of a movable universal bar, dogs or pawls pivoted to said universal bar, ratchet wheels secured to the shaft sections to be engaged by said dogs or pawls, pivoted L-shaped 85 arms, each having a member projecting under one of said dogs or pawls, a longitudinally movable shift bar pivotally connected with said L-shaped arms, and an operating arm projecting from said shift bar. 90

3. In ribbon mechanism for typewriting machines, the combination with two shafts, alining shaft sections geared to said shafts, and ratchet wheels secured to said shaft sections, of a movable universal bar, dogs carried by said universal bar and adapted to engage the ratchet wheels, L-shaped arms pivotally supported at one end and projecting at their other ends under said dogs or pawls, a longitudinally movable shift 95 bar pivotally connected at its ends with the respective L-shaped arms, ribbon reels mounted on the first mentioned shafts and each provided with a hub having a recess 100 and projecting beyond said reel, a spring actuated hinged section for each hub for spanning the recess therein, pivoted arms having rollers to run on the projecting portions of said hubs and adapted to enter the recesses in latter when the hinged sections 110 thereof are open, and arms projecting from the shift bar in position to be engaged by one or the other of said last mentioned pivoted arms when the same is permitted to move so as to allow its roller to enter one 115 of said sleeves or hubs.

In testimony whereof, I have signed this specification in the presence of two subscribing witnesses.
